UNITED STATES PATENT OFFICE.

JOSEPH H. BURROWS, OF BROCKTON, MASSACHUSETTS, ASSIGNOR TO BURROWS LOCK-NUT & BOLT COMPANY, OF BEVERLY, MASSACHUSETTS, A CORPORATION OF MASSACHUSETTS.

NUT-LOCK.

No. 893,567.

Specification of Letters Patent. Patented July 14, 1908.

Application filed March 4, 1908. Serial No. 419,098.

To all whom it may concern:

Be it known that I, JOSEPH H. BURROWS, a citizen of the United States, residing at Brockton, in the county of Plymouth, State of Massachusetts, have invented an Improvement in Nut-Locks, of which the following description, in connection with the accompanying drawings, is a specification, like numerals on the drawings representing like parts.

10 This invention relates to a nut having a cavity opening into the threaded bolt hole of the nut, and a thread indenting key inserted in said cavity, and having a sharpened inner end adapted to indent the threads of the bolt 15 with which the nut is engaged, to prevent the removal of the bolt from the nut, the key and the recess having interengaging members, all of which permits an endwise rocking movement of the key, so that it may be 20 swung inwardly toward the bolt to indent the thread thereof, and outwardly from the bolt to release the thread and to permit the removal of the nut.

One object of the invention is to provide 25 improved means for establishing a loose locking engagement between the key and the bottom of the cavity, which shall permit the necessary rocking movement of the key, and at the same time prevent the removal of the 30 key from the cavity.

Another object of the invention is to enable the key to be rocked to and from its locking position by force applied to the key outside of the cavity, so that the key may be 35 rocked without the employment of a special tool adapted to enter the cavity.

My invention will be best understood by reference to the following description, taken in connection with the accompanying illustration of one specific embodiment thereof, while its scope will be pointed out in the appended claims.

40 Of the accompanying drawings forming a part of this specification,—Figure 1 represents a sectional view of a nut provided with a cavity adapted to contain a locking key, the cavity having a key-engaging member embodying a portion of my invention; Fig. 2 represents a side view of the key which is 45 to be inserted in the cavity shown in Fig. 1; Fig. 3 represents an edge view of the key; Fig. 4 represents a sectional view of a portion of the nut showing the key in its locking position in the cavity of the nut; Fig. 5 represents a view similar to Fig. 4, showing the

key rocked to its unlocking position; Fig. 6 represents an end view of the portion of the nut which contains the cavity; and Figs. 7 and 8 represent views showing slight variations in the form of the socket member in 60 the key.

The same numerals of reference indicate the same parts in all the figures.

In the drawings 12 represents a nut having the usual threaded bolt hole 13, and having 65 also a slot-shaped cavity 14, one end of which is opened into the bolt hole and the top of which opens through the exterior upper face of the nut.

15 represents a stud member which projects upwardly from the bottom of the cavity 14, and is preferably formed as a web, with the nut, and extends across the cavity, as shown in Fig. 6.

16 represents a locking key, which is inserted in the cavity 14, and is sharpened at 70 its inner end to form a cutting edge 17, adapted to indent the thread of a bolt with which the nut is engaged. The lower edge portion of the key is provided with a socket 75 portion 18, which is formed to have a loose rocking engagement with the member 15, the form of said member being such that the key is adapted to stand in the locking position shown in Fig. 4, with its cutting edge indent-

80 ing the bolt thread, or in the unlocking position shown in Fig. 5, with its cutting edge withdrawn from the bolt. The width of the outer end of the stud member 15 is greater than that of the inner end or base portion of 90 the stud member. The socket portion 18 has a contracted mouth, which is narrower than the outer end of the stud member. The inner end of the socket portion is considerably wider than the wider outer end of the 95 stud member, the proportions and relative engagement of the stud member and socket portion being such that the widened inner end of the socket portion permits the key to rock on the stud member, while the widened outer end of the stud member and the contracted mouth of the socket portion prevent the removal of the key from the cavity 14.

In practice the widening of the outer end of the stud member is preferably effected by 105 the upsetting of the upper end or edge of the stud member, which is upset from its form or shape shown in Fig. 1 to that shown in Fig. 4, by the pressure of the inner wall of the socket portion which is directed to cause 110

the stud member to swell out within the widened portion of the socket to a greater width than the narrow width of the socket. This pressure is caused by driving the key 5 downwardly into the cavity 14 in the direction indicated by the arrow in Fig. 4, the inner wall of the socket member being thus caused to bear upon the upper edge 19, of the stud and force the same outwardly, thus 10 augmenting the width of the outer end of the stud member, and causing the width of said outer end to exceed the width of the contracted mouth of the socket. Care is taken, however, to have the width of the inner end 15 of the socket exceed the augmented width of the outer end of the stud member, so that notwithstanding the said augmentation, the key is adapted to rock on the stud member. The initial or original height of the stud will 20 of course be selected sufficiently in excess of the depth of the socket to permit the needed augmentation of its upper end when upset, all with reference to the other proportions of the several coöperating parts.

25 It will be seen from the foregoing that provision is made for loosely locking the key to the nut by the act of forcing it into the cavity 14, the loose locking of the key being effected wholly by complementary members 30 provided at the bottom portion of the cavity at the inner edge portion of the key. Heretofore in nut locks of this character, the removal of the key from the cavity has been by indenting or upsetting portions of the outer 35 surface of the nut at opposite sides of the cavity, to cause said portions to overhang the key, and contract the mouth of the cavity. This contraction of the mouth of the cavity is objectionable because it interferes with the free rocking movements of the key, an objection which is entirely overcome by my invention above described. The outer side 20 of the socket 18 is made shorter than the inner side 21, to permit the 40 rocking of the key from its locking to its unlocking position, as clearly illustrated in Figs. 4 and 5.

The width of the key is such that its outer edge projects above the outer face of the nut, 50 and is therefore adapted to be engaged by a hammer or other like tool, applied to the key outside of the cavity 14. Heretofore in nut locks of this character, it has been necessary to form the key so that its outer edge is within 55 the outer face of the nut, in order that the key may be retained by upsetting portions of the outer face of the nut, and contracting the mouth of the cavity, as above described. It has therefore been necessary heretofore to 60 apply pressure to the key by means of a special tool, such as a nail set, having a narrow end adapted to enter the mouth of the cavity, and bear upon the outer edge of the key within the cavity. It will be seen that 65 the extension of the key outside the cavity,

which is made feasible by the loose interlocking of the inner portion of the key with the bottom of the cavity, enables any convenient driving tool, such as a hammer, to be used in rocking the key, the shape of the driving tool being immaterial, so that a tool of much greater width than the width of the cavity may be employed.

I prefer to provide the projecting portion of the key with a protuberance 23, presenting 75 a sloping or beveled portion 24 which faces outwardly from the bolt hole and enables a hammer to be applied conveniently to the key in the direction indicated by the arrow in Fig. 5. The outer portion 25 of the upper 80 edge of the key also projects above the outer face of the nut, and forms a bearing for a hammer applied in the direction required to rock the key to its unlocking position.

As shown in Fig. 3, the transverse dimension or the thickness of the key is substantially the same as the width of the slot or cavity 14, so that the key enters the cavity with a driving fit. The resultant friction upon the flat faces of the key, therefore, acts 90 to hold the same in engagement with the bolt threads when driven into engagement therewith, and also to hold the key tipped back into the position shown in Fig. 5 when rocked out of engagement therewith. 95

My invention is not limited to the particular form of the interlocking members of the key and nut here shown, as the same may be variously modified without departing from the spirit of the invention. In Figs. 100 7 and 8 I show modified forms of the inner end of the socket member 18 of the key.

Claims.

1. A nut having a slot-shaped cavity opening into the bolt hole and also upon the exterior surface of the nut, and a thread-indenting key inserted in said cavity, the inner edge portion of the key and the bottom of the cavity having interlocking but loosely fitting members, one upon the nut and the other 105 upon the key, which permit the endwise rocking of the key without necessary deformation of the same interlocking members, and prevent the removal of the key from the cavity. 110

2. A nut having a slot-shaped cavity opening into the bolt hole and also upon the exterior surface of the nut, a stud member projecting outwardly from the bottom of the cavity, and a thread-indenting key inserted in the 115 cavity, and having an edge provided with a socket loosely engaged with the stud member, the stud and socket being formed to prevent the removal of the key from the cavity, but to permit the key to rock endwise therein 120 without necessary deformation of the stud. 125

3. A nut having a cavity opening into the bolt hole, a stud member projecting outwardly from the bottom of the cavity, and of greater width at its outer than at its inner 130

end, and a thread-indenting key inserted in the cavity and provided with a socket loosely engaging the stud of the cavity and having a contracted mouth which is narrower than the outer end of the stud member, and an inner end which is wider than the outer end of the stud member, whereby endwise rocking of the key is permitted, and its removal from the cavity is prevented.

10 4. A nut having a slot-shaped cavity opening into the bolt hole and also upon the exterior surface of the nut, and a thread-indenting key inserted in said cavity, and projecting outwardly from the mouth of the latter, for engagement with a driving tool, the inner edge portion of the key and the bottom of the cavity having interengaged but loosely fitting members which permit the endwise rocking of the key without necessary deformation of the said members.

15 5. A nut having a slot-shaped cavity opening into the bolt hole and also upon the exterior surface of the nut, and a thread-indenting key inserted in said cavity, and projecting outwardly from the mouth of the latter for engagement with the driving tool, the inner edge portion of the key and the bottom of the cavity having interengaged but loosely fitting members which permit end- 20 wise rocking of the key without necessary

deformation of said members, and prevents the removal of the key from the cavity.

6. A nut having a slot-shaped cavity opening into a bolt hole and also upon the exterior surface of the nut, a thread-indenting key inserted in said cavity, said key having means providing for a rocking engagement with the nut said means comprising a co-operating socket and stud member, one upon the edge of the key and the other upon the bottom of the slot-shaped cavity and having a thread-indenting edge adapted to engage the threads of the bolt to lock the same in position when the key is driven forward about its fulcrum point, said key being proportioned when in its interlocked position to present a projecting portion outside the limits of said cavity and at the opposite side of the fulcrum from the indenting edge, whereby the said projecting portion may be struck by a suitable tool and the key rocked endwise to an unlocking position.

In testimony whereof, I have signed my name to this specification, in the presence of two subscribing witnesses.

JOSEPH H. BURROWS.
